UNITED STATES PATENT OFFICE

148,700

DESIGN FOR A CONTAINER FOR TOYS AND THE LIKE

T. Barry Hodge, Chicago, Ill.

Application November 29, 1945, Serial No. 124,197

Term of patent 3½ years

(Cl. D58—12)

To all whom it may concern:

Be it known that I, T. Barry Hodge, a citizen of the United States of America, residing at Chicago, in the county of Cook and State of Illinois, have invented a new, original, and ornamental Design for a Container for Toys and the like, of which the following is a specification, reference being made to the accompanying drawing, forming a part thereof.

Fig. 1 is a top and side perspective view of a container for toys and the like showing my new design.

Fig. 2 is a bottom and side perspective view thereof.

The dominant feature of my design resides in the surface ornamentation, and particularly the surface on the top of the box as shown in Figure 1.

I claim:

The ornamental design for a container for toys and the like, substantially as shown and described.

T. BARRY HODGE.
